(57) CLAIM

The ornamental design for a hair styling iron, as shown, and described.

DESCRIPTION

FIG. 1 is a perspective view of the hair styling iron;
FIG. 2 is a top view of the hair styling iron;
FIG. 3 is a bottom view of the hair styling iron;
FIG. 4 is a side view of the hair styling iron;
FIG. 5 is a rear view of the hair styling iron; and,
FIG. 6 is a front side view of the hair styling iron.
The broken lines shown in the drawings illustrate portions of the hair styling iron and form no part of the claimed design.
